UNITED STATES PATENT OFFICE.

HARRY P. McCANN, OF LAKWOOD, OHIO.

FURNACE AND METHOD OF CONVEYING MATERIALS THERETHROUGH.

1,400,367.

Specification of Letters Patent. Patented Dec. 13, 1921.

Application filed September 10, 1919. Serial No. 323,038.

To all whom it may concern:

Be it known that I, HARRY P. McCANN, a citizen of the United States, residing at Lakewood, in the county of Cuyahoga and 5 State of Ohio, have invented certain new and useful Improvements in Furnaces and Methods of Conveying Materials There- through, of which the following is a specifi- cation.

10 My invention relates broadly to furnaces used for metallurgical purposes but more particularly to what are known as heat- treating furnaces through which the mate- rials to be treated are conveyed at such a 15 rate of travel as to permit the heat of the furnace to bring them to the desired condition before they are removed or discharged from the furnace.

Among the objects of my invention are 20 the provision of a furnace in which the ma- terials are uniformly and accurately heated as they are conveyed through the furnace; the provision of a simple and practical means for conveying materials through a 25 heated furnace without serious deterioration of the conveyer mechanism from the action of heat; the provision of an improved method of conveying materials through a furnace; and the provision of means for conveying 30 separate articles through a furnace and maintaining them in regular spaced-apart re- lation to each other.

These and other objects of my invention are attained by the use of my invention de- 35 scribed herein and illustrated in the accom- panying drawings in which—

Figure 1 is a vertical longitudinal section through a furnace embodying my invention;

Fig. 2 is a vertical transverse section on 40 line II—II of Fig. 1;

Fig. 3 is a vertical transverse section on line III—III of Fig. 1;

Fig. 4 is a vertical longitudinal section of 45 a modified form of furnace embodying my invention;

Fig. 5 is a vertical transverse section on line V—V of Fig. 4;

Fig. 6 is a vertical transverse section on line VI—VI of Fig. 4;

50 Figs. 7, 8, 9 and 10, show the work-mov- ing or conveyer member of the structure shown in Fig. 1 in the different positions

taken by it in performing its series of move- ments.

In the preferred embodiment of my in- 55 vention, as illustrated in Figs. 1, 2 and 3, there is shown a form of conveyer adapted to move the materials, commonly called the work, to be treated through the furnace step by step and to maintain them in regular and 60 orderly spaced-apart relation to each other. To accomplish this desired movement of the work through the furnace I provide a hearth, 1, having a longitudinal slot or slots, 2, therein, in which there is disposed a work- moving or conveying member or members, 3. The work, which for purposes of illus- 65 tration is shown in the drawings as consist- ing of flat bars, 4, is placed upon the hearth so that it spans the slot in which the work- moving member operates. To convey the work through the furnace in the desired manner stated above there is imparted to the work-moving member, by suitable mech- 70 aism, a series of movements as follows: the work-moving member is first raised verti- cally upward into contact with the work and lifts the work bodily off the stationary or work-supporting hearth; the work-moving member is then given a longitudinal, for- 75 ward movement for a short distance carry- ing with it the work which it has lifted off from the hearth; the work-moving member is then lowered downward depositing the work upon the stationary hearth and con- 80 tinuing in its downward movement to be entirely out of contact with the work; the work-moving member is next moved longitu- 85 dinally backward to the place where it be- gan its initial upward movement. This se- ries of operations is repeated regularly and indefinitely, the work being supplied to the inlet end of the furnace and discharged or 90 removed from the outlet end of the fur- nace continuously, or, if desired, the opera- 95 tion of the work-moving member may be stopped, after the work is in the furnace, to give the work time to be heated to the tem- perature and for the period necessary.

I am aware that conveyers intended to 100 move work through furnaces by step by step movement have been proposed but in those furnaces with which I am familiar the work- moving or conveying members are given a

combined vertical and longitudinal movement instead of separate and distinct vertical and longitudinal movements such as I employ. My method of conveying materials through a furnace has marked advantages over the former methods for the reason that in my method the work is lifted vertically off from the hearth and the longitudinal forward movement does not commence until the work is out of contact with the hearth. In a similar manner in my method the work is deposited vertically downward upon the hearth after the longitudinal forward movement has entirely ceased. By this method of moving the work it is possible to maintain individual pieces of work in orderly and regular spaced-apart relation to each other. This is not possible in furnaces in which the work describes cyclic or arcuate paths, in which the vertical and longitudinal movements are combined and take place simultaneously, as the surface of the hearth is always more or less uneven and the work either varies originally in shape or is warped by the heat of the furnace so that the work-moving member does not come into contact at the same time with all of the pieces of work in the furnace and consequently the pieces of work frequently become misplaced, contact with each other in the furnace, and pile up and clog the furnace, resulting in delays and damage to the work and the furnace.

Opening out of the slots, 2, are waste gas flues, 5, which connect with other suitable ducts, 6, leading to the atmosphere or to a waste gas hood or stack, not shown, which may be provided.

The heating gases may be introduced directly into the furnace chamber, 7, or better, as shown in Figs. 3 and 6, they may be introduced into the combustion chamber, 8, and thence passed through suitable distributing ports, 9, in the checker-work top, 10, of the furnace chamber, 7. For serving the furnace I have shown, conventionally, the gas or oil burner, 11, but it will be understood that any suitable fuel or means of heating the furnace may be employed and that any number of openings for the introduction of the heating gases may be employed.

I prefer to construct the walls, 12, bottom, 13, and top, 14, of highly refractory materials and support the furnace upon a base such as 15, which may be of any suitable material, not necessarily highly refractory, as in the operation of my furnace the parts below the bottom, 13, are not subjected to extremely high temperatures.

The work-moving members, 3, which are preferably made of refractory material and constitute movable sections of the hearth, 1, are carried by suitable chairs, 16, supported upon beams, 17. The refractory work-moving members, 3, are preferably constructed

of a plurality of similar blocks or sections, 18, having openings, 19, extending through them. The sections, 18, are so placed that the openings, 19, register with the flues, 5. The blocks, 18, extend downward through the slots, 2, and are made narrower than the slots so as to form clearance spaces, 20. These clearance spaces, 20, serve also as outlets for the waste gases from the furnace chamber, 7. Longitudinal openings or slots, 21, for the supports, 16, and beams, 17, are provided in the base, 15. Other suitable chambers, such as 22, 23, 24 and 25, are provided in the base 15, for the accommodation of the operating mechanism of the work-moving members, these chambers being preferably closed to the outer atmosphere.

It will be seen that the slots, 2, extend clear through the hearth, 1, of the furnace into the openings, 21, and that clearance spaces, 26, are provided between the work-moving members, 3, and the walls of the slots, 2, below the flues, 5.

In the operation of my furnace the gases of combustion after they have served their purpose in the furnace chamber, 7, pass downward through the clearance spaces, 20, between the work-moving members, 3, and the walls of the slots, 2, into the waste gas flues, 5, and thence are conducted through the ducts, 6, to the atmosphere or stack. As the direction of flow of gases in the clearance spaces, 20, is always downward and out of the furnace chamber there is no opportunity for the entrance of air or cold gases through them to cool the work which is located above them. Should there be any leakage of cold air into the slots, 21, and clearance spaces, 26, it will be drawn into flues, 5, and pass out through ducts, 6, with the waste gases from the furnace chamber, and will not enter the furnace chamber. Uniform heating of the work in the furnace is assured by the construction above described and chilling of the work by the introduction of cold air through the slots, 2, cannot occur. It will be understood that a slight plus pressure or static can be readily maintained in the work chamber, 7, of the furnace which pressure will force the gases of combustion to the flue openings, 5, in the hearth bottom. The hot gases in the outlet flues, 6, produce a draft or minus pressure at the hearth line and the combined action of the plus pressure in the work chamber and the minus pressure or flue draft produces the required circulation of the hot gases through the work chamber and out of the flues, 5. The heat from these gases uniformly heats the hearth and the work thereon.

To prevent seepage of air into the openings provided in the foundations for the accommodation of the operating mechanism, covers or doors such as are shown at 27, 28, 130

and 29 may be provided. Owing to these covers or closures a dead air space is maintained in the chambers beneath the furnace hearth in which the metal parts of the hearth 5 operate, which, in connection with the flue arrangement, prevents the hot gases from entering these chambers and makes it unnecessary to provide any special arrangement for cooling these metal parts.

- 10 The operating mechanism for the work-moving members of the form of my invention shown in Figs. 1, 2 and 3, is constructed as follows: The beams, 30, are connected by means of a pitman, 31, to a power-driven 15 crank-pin, 32, of the power-driven crank-shaft, 33, the end of the pitman which receives the crank-pin, 32, being slotted longitudinally as shown at 34 for a purpose which will be described. Crank-shaft, 33, being 20 rotated by any suitable power connection causes the cross-beams, 30, and consequently longitudinal beams, 17, and the work-moving member, 3, to travel longitudinally back and forth in the slots, 2, while the slot, 34, in 25 the pitman, 31, permits the work-moving member to remain stationary at either end of its travel, the time during which it is stationary depending upon the length of the slot, 34.
- 30 In the construction shown in Figs. 1, 2 and 3, the beams, 17, are supported by cross-beams, 30, which in turn rest upon longitudinal guides or bearing plates, 35. The guides, 35, are, in turn, carried by rollers, 36, which rollers are rotatably mounted on levers, 37. Levers, 37, are mounted upon and secured to shafts, 38, which are supported in bearings, 39. The bearings, 39, are supported by the foundation, 40. Mounted upon the shaft, 38, and secured thereto for rotation therewith are the levers, 41, to the outer ends of which is pivoted the common connecting rod, 42, which is provided with suitable length adjusting turn-buckles, 43. The connecting rod, 42, is pivoted at one end to lever, 44, which is operated by a cam, 45. For this purpose the lever, 44, is fulcrumed at 46, and is provided with a cam roller, 47. Cam, 45, is mounted upon and 50 secured for rotation with shaft, 48, which shaft is geared to crank-shaft, 33, so as to rotate at the same speed. It will be seen that cam, 45, is so shaped that when it is rotated by cam shaft, 48, the work-moving member, 3, will be raised vertically upward during part of one revolution of the cam, 45; will be sustained in its uppermost position during another part of the revolution of the cam; will be lowered during another part 55 of the revolution of the cam; and will remain stationary in its lower position for the last portion of the revolution of the cam. The crank-pin, 32, and the cam, 45, are so located upon crank-shaft, 33, and cam-shaft, 48, respectively, that the longitudinal move-

ments of the work-moving member, 3, alternate with its vertical movements as follows: As seen in Fig. 7, the work-moving member, 3, is in its forward and lower position. If now the crank-shaft, 33, be revolved in a 70 counterclock-wise direction as seen in this figure, it will cause the pitman, 31, to draw the work-moving member toward the rear or right-hand end of the furnace to the position shown in Fig. 8. The cam-shaft, 48, 75 will, at the same time revolve in a counterclock-wise direction and for a portion of its revolution the cam, 45, will not cause any vertical movement of the work-moving member. After the crank-shaft, 33, has carried its crank-pin, 32, to the right-hand end of its travel the work-moving member, 3, will remain stationary so far as the longitudinal movement is concerned while the crank-shaft 80 revolves so as to bring the crank-pin, 32, into contact with the opposite end of its slot. During the time that there is no longitudinal movement of the work-moving member, 3, cam, 45, operates upon lever, 44, to lift work-moving member, 3, vertically upward to the position shown in Fig. 9, by the action of the mechanism described which includes the connecting rod, 42, levers, 41, shaft, 38, levers, 37, and rollers, 36. When the work-moving member, 3, has been moved to its upper position it is held there by cam, 45, while the work-moving member, 3, is moved longitudinally forward to the position shown in Fig. 10 by the pitman, 31, operated by crank-shaft, 33, and crank-pin, 32. At the forward end of the longitudinal movement of the work-moving member, 3, there is another rest period on account of the lost motion allowed between the crank-pin, 32, and the pitman, 31, by the slot, 34. During this rest period, cam, 45, permits the work-moving member to descend to its forward and lower position by gravity, the roller 47, of lever, 44, contacting with cam, 45, to control this lowering movement. Work-moving member, 3, has now completed one series of its movements, which series is repeated so long as the shafts, 33 and 48, are rotated.

As the work-moving member rises at the rear end of its travel it lifts the work, such as shown at 4, bodily off from the hearth and carries it vertically upward; the next movement of the work-moving member which is longitudinally forward carries the work with it; the third movement of the work-moving member which is vertically downward deposits the work upon the stationary hearth bottom; and the last movement of such a series of movements of the work-moving member is to carry it longitudinally back to the place of beginning. On account of the separation of the vertical and longitudinal movements of the work-moving member there is no opportunity for the work

to drag upon the stationary hearth such as occurs where cyclic or combined vertical and longitudinal movements are imparted to the work-moving member.

- 5 5 To counterbalance in a large measure the weight of the work-moving member and the work, counterweights, 49, may be provided, suspended from the levers, 37, in the manner shown in Fig. 1.
- 10 10 In the modified form of my invention shown in Figs. 4, 5 and 6, the flues, 50, conduct the gases of combustion from the longitudinal slots in the hearth bottom to the longitudinal ducts or flues, 51, which are 15 connected to up-take flues, 51^a, in the end wall of the furnace. The mechanism for operating the work-moving member vertically is also somewhat modified in that the cross-beams, 30, are omitted and the longitudinal beams, 17, rest directly upon rollers, 52. The rollers, 52 are carried in suitable bearings supported upon cross-beams, 53, which are given periodic vertical movements by a mechanism similar to that shown in 20 Figs. 1, 2 and 3, and described above. In the furnace shown in Figs. 4, 5 and 6, means is provided for opening and closing the door, 54, of the furnace in harmony with the movement of the work-moving member 25 so that the door will be open while the work is being fed into the furnace and will be closed during the backward movement of the work-moving member. For this purpose the furnace door, 54, has secured to it the chains, 55, or other suitable devices, which are connected to the walking-beams, 56, which are pivoted upon supports, 57. The walking-beams, 56, are connected by rods, 58, to levers, 59, and oscillate to raise and 30 lower the door, 54, in synchronism with these levers as they are operated by the driving mechanism to raise and lower the work-moving members. It will be seen that the door, 54, will remain closed during the 35 backward movement of the work-moving members and open during their forward movement. The closing of the door, 54, economizes heat and aids in securing uniform heating of the work. In the construction 40 of the furnace shown in Figs. 1, 2 and 3, there are shown, at 60 and 61, inlet and outlet openings respectively for the work at the ends of the furnace while in the construction shown in Figs. 4, 5 and 6, the outlet opening, 62, for the work is shown at 45 one side of the furnace.
- 50 50 On account of different widths of work it is sometimes an advantage to be able to change the longitudinal travel of the work-moving members. For this purpose the throw of the crank which actuates the work-moving member longitudinally may be varied by moving the crank-pin, 32, radially 55 toward the center of crank-shaft, 33, to 60 shorten the longitudinal travel of the work-

moving member or away from the center of crank-shaft, 33, to lengthen the travel. This may be done by providing holes such as are shown at 63, 64 and 65, in Fig. 4, at various distances from the center of crank disk in which the crank-pin, 32, may be secured. In order to maintain the correct angular relation of the shafts, 33 and 48, when the position of the crank pin, 32, is changed to one of the other holes, 63, 64 or 65, the shaft, 33, may be taken out of its bearings and rotated a portion of a revolution and then replaced in its bearings with the gears which form the driving connection between shafts, 33 and 48, in proper engagement to maintain the desired relative positions of the crank pin, 32, and cam, 45. It is obvious that if crank pin, 32, be placed in the center of the end of shaft, 33, there will be no horizontal movement of the work-moving member. It is also obvious that if the slot, 34, in the pitman, 31, be as long as the throw of the crank plus the diameter of pin, 32, there will be no horizontal movement of the work-moving member.

Instead of employing the several holes, 63, 64 and 65, for changing the throw of the crank a radial slot may be provided in the crank disk in which the crank pin may be secured at any desired distance from the center in a well known manner. In such construction it is unnecessary to alter the relative angular positions of the shafts, 33 and 48, when making a change in the longitudinal travel of the work-moving member. Any other convenient means for varying the length of the longitudinal travel of the work-moving member may be employed.

It will be understood that I do not limit my invention to the particular construction which I have illustrated. For instance, it is obvious that shafts, 33 and 48, may be combined in one shaft, the cam, 45, being mounted upon the same shaft that carries crank-pin, 32, provided that the proper angular positions of cam 45, and crank-pin, 32, upon the single shaft be maintained.

The modifications which I have described and other modifications may be made without departing from the scope of my invention.

Having thus described my invention I claim:

1. In a furnace heated by gases of combustion, a heating chamber having a hearth having a longitudinal slot therein, and a work-moving member disposed in said slot, said slot being wider than said work-moving member forming clearance spaces between said work-moving member and the walls of said slot, and a flue in said hearth connected to said slot for conducting the waste gases of combustion away from it.
2. In a furnace heated by gases of combustion, a heating chamber having a hearth

having a plurality of longitudinal slots therein, work-moving members disposed in said slots, said slots being wider than said work-moving members forming clearance spaces between said work-moving members and the walls of said slots, flues in said hearth connecting said slots and flues in said hearth connected to said slots for conducting the waste gases of combustion away from them.

3. In a heat-treating furnace in which the articles to be treated are caused to move step by step in spaced apart relation through the work-chamber, a work-chamber provided with a stationary work-supporting hearth, said hearth having a slot extending longitudinally through it, a work-moving member disposed in said slot adapted when operated to first rise into contact with and lift the work vertically off from said hearth, then to advance it a step longitudinally at a uniform height above and out of contact with said hearth, then to lower it vertically to rest upon said hearth the work-moving member descending out of contact with the work, and finally to return out of contact with the work longitudinally backward to the starting point, and means for operating said work-moving member.

4. In a heat-treating furnace in which the articles to be treated are caused to move step by step in spaced apart relation through the heating chamber, a heating chamber provided with a stationary work-supporting hearth, said hearth having a slot extending longitudinally through it, a work-moving member disposed in said slot adapted when operated to first rise into contact with and lift the work vertically off from said hearth, then to advance it a step longitudinally along but out of contact with said hearth, then to lower it vertically to rest upon said hearth the work-moving member descending out of contact with the work, and finally to return out of contact with the work longitudinally backward to the starting point, means for moving said work-moving member longitudinally comprising a pitman pivoted at one end to the work-moving member and at the other end to a power-driven crank, one end of said pitman being slotted longitudinally to receive its pivot to permit the work-moving member to rest in its longitudinal movement at each end of its travel while it is being vertically raised or lowered, and means for moving said work-moving member vertically comprising a vertically moving support for said work-moving member, and means operating synchronously with the rotation of said crank for raising and lowering said support and said work-moving member during the rest periods of the work-moving member at the backward and forward limits of its travel respectively.

5. A furnace having a hearth bottom composed of a stationary portion and a movable portion, said stationary and movable portions being spaced apart transversely of the hearth to form an opening between them for the escape of the gases of combustion used for heating the furnace, and said opening being connected to a waste gas flue in said stationary portion of said hearth bottom adapted to conduct said gases of combustion away from the furnace.

6. A furnace conveyer comprising a work support and a work-moving member disposed side by side, said work-moving member being adapted to move vertically and longitudinally relative to said work support and means in operative engagement with said work-moving member adapted when operated to move said work-moving member first upward, then longitudinally forward at a uniform height, then downward and then longitudinally backward.

7. A furnace conveyer comprising a work support and a work-moving member disposed side by side, said work-moving member being adapted to move vertically and longitudinally relative to said work support, means connected to said work-moving member adapted when operated to impart longitudinal reciprocating motion thereto, lifting means connected to said work-moving member adapted when operated to impart vertical reciprocating motion thereto, and mechanism connecting said first named means and said lifting means whereby the longitudinal movement of said work-moving member takes place in one direction while it is at the highest point of its vertical movement and in the opposite direction while it is at the lowest point of its vertical movement.

8. A furnace comprising a heating chamber provided with a hearth having a longitudinal slot therein, means for supplying heating gases to the heating chamber, a work-moving member disposed in said slot adapted to convey the work through said heating chamber, said slot being wider than said work-moving member forming an opening between them for the escape of the gases of combustion from the heating chamber, and means including a flue in said hearth connected to said slot for conducting said gases of combustion away from said opening.

9. In a furnace a hearth bottom having a stationary work-supporting portion, and a movable work-moving portion disposed side by side with a space between them, said work-moving portion being adapted to have vertical and longitudinal reciprocating movements relative to said work-supporting portion, means for moving said work-moving portion vertically, means for moving said work-moving portion longitudinally at

a uniform height, and mechanism connecting said means whereby the vertical and longitudinal movements take place in the following order, vertically upward, longitudinally forward at a uniform height, vertically downward and longitudinally backward to the place of beginning.

10. In a furnace a hearth bottom having a stationary work-supporting portion, and a movable work-moving portion disposed side by side with a space between them, said work-moving portion being adapted to have vertical and longitudinal reciprocating movements relative to said work-supporting portion, means for moving said work-moving portion vertically, means for moving said work-moving portion longitudinally at a uniform height, and mechanism connecting said means whereby the vertical and longitudinal movements take place in the following order, vertically upward, longitudinally forward at a uniform height, vertically downward and longitudinally backward to the place of beginning, and a waste gas flue in said hearth bottom connected to said space for conducting the waste gases away from the furnace.

11. In a furnace a hearth bottom having a longitudinal slot, a work-moving member disposed in said slot with clearance spaces between it and the walls of said slot, said work-moving member being adapted to convey the work longitudinally through the furnace, and a waste gas flue in said hearth bottom connected to said slot.

12. The method of conveying materials through a furnace which consists of first placing them upon the hearth of the furnace and then advancing them through the furnace by step by step progression each step consisting of a vertically upward movement off from the hearth, a longitudinally forward movement at a uniform height above and out of contact with the hearth, and a vertically downward movement to the hearth.

13. In a heat treating furnace in which the articles to be treated are caused to move step by step in spaced apart relation through the work chamber, a work-chamber provided with a stationary work-supporting hearth, said work-chamber having an opening at one end for the admission of the articles to be treated, a vertically moving door adapted to close said opening, said stationary work-supporting hearth extending outward through said opening, a work-moving member extending longitudinally through said work-chamber and said opening, said work-moving member being adapted when operated to move in repeated cycles, vertically up, horizontally forward, vertically down and horizontally backward to move the work step by step through the furnace, means for operating said work-moving member, and means

connecting said operating means and said door whereby opening and closing movements of said door are caused to take place respectively with the upward and downward movements of said work-moving member.

14. A furnace conveyer comprising a work support and a work-moving member disposed side by side, said work-moving member being adapted to move vertically and longitudinally relative to said work support, means for reciprocating said work-moving member longitudinally, means for reciprocating said work-moving member vertically, and means for varying the length of the longitudinal reciprocating movements of said work-moving member.

15. A furnace conveyer comprising a work support and a work-moving member disposed side by side, said work-moving member being adapted to move vertically and longitudinally relative to said work support, means for reciprocating said work-moving member vertically and longitudinally and means for varying the length of the longitudinal reciprocating movements without changing the length of the vertical reciprocating movements of said work-moving member.

16. A furnace conveyer comprising a work support and a work-moving member disposed side by side, said work-moving member being adapted to move vertically and longitudinally relative to said work support, mechanism connected to said work moving member adapted when operated to impart separate vertical and longitudinal movements to said work-moving member and means for varying the extent of said longitudinal movements.

17. In a heat-treating furnace in which the articles to be treated are caused to move step by step in spaced apart relation through the heating chamber, a heating chamber provided with a stationary work-supporting hearth, said hearth having a slot extending longitudinally through it, a work-moving member disposed in said slot adapted when operated to first rise into contact with and lift the work vertically off from said hearth, then to advance it a step longitudinally along but out of contact with said hearth, then to lower it vertically to rest upon said hearth the work-moving member descending out of contact with the work, and finally to return out of contact with the work longitudinally backward to the starting point, means for moving said work-moving member longitudinally comprising a pitman pivoted at one end to the work-moving member and at the other end to a power-driven crank, one end of said pitman being slotted longitudinally to receive its pivot to permit the work-moving member to rest in its longitudinal movement at each end of its travel while it is being vertically raised or lowered, means

for varying the longitudinal movement of said work-moving member, and means for moving said work-moving member vertically comprising a vertically moving support for 5 said work-moving member, and means operating synchronously with the rotation of said crank for raising and lowering said support and said work-moving member during the rest periods of the work-moving member at the backward and forward limits of its travel 10 respectively.

In testimony whereof I affix my signature.

HARRY P. McCANN.
